CONTROL SYSTEM FOR REWINDER REEL DRIVES

Albert T. Bacheler, Wilkinsburg, and Thomas M. Greer, Pittsburgh, Pa., assignors to Westinghouse Electric Corporation, East Pittsburgh, Pa., a corporation of Pennsylvania

Application May 14, 1949, Serial No. 93,298

8 Claims. (Cl. 318—7)

1

This invention relates to electric control systems for rewinder drives. Such drives serve to wind textile, paper, metal, or other material from one reel core to another in one or the other winding direction, usually at a substantially constant speed of linear travel and within a given range of tension of the material. This requires one reel motor to increase its revolving speed while the material is unwound from the appertaining reel core, while the motor for the take-up reel decreases its speed as the diameter of the appertaining reel of material is building up. For some applications, such as in a dye jig, the reel drive must be reversible so that the material can be passed back and forth between the two reels for repetitive fabricating or processing operations.

It is an object of our invention to provide a rewinder drive control system which satisfies the above-mentioned requirements by means of a very simple circuit design whose torque-regulating performance does not rely on the use of reel-operated rheostats or other contact or slide-contact devices, such as dancer roll operated rheostats.

It is another object of our invention, subsidiary to the one mentioned, to provide a rewinder drive control system whose reel motors have armature circuits of utmost simplicity that do not require the insertion of power consuming devices for performing the desired speed or tension control.

In order to achieve these and the more specific objects apparent from the following description, we connect the armatures of the two correlated reel drive motors in series to a source of current so that both armatures are traversed by the same current in the respective directions needed to have each motor exert a torque in the wind-up direction. We further connect the respective field windings of the motor in a network, preferably of the bridge type, which is energized from two voltage sources so that their voltages are cumulative for the field of one motor and differential for the field of the other motor. One of the sources provides a normally constant voltage, while the other source is a regulator, preferably of the amplifying type such as an amplifying generator, and provides a variable regulating voltage under control by the sum of the respective voltages across the two motor armatures.

While these and other features of our invention are set forth in the appertaining claims, a more detailed example and explanation are given in the following description with reference to the drawing which shows diagrammatically a rewinder drive control system for a dye jig.

2

In the drawing, a trough for the dye is denoted by 1. Two rolls or reel cores 2 and 3 are provided for passing the textile or other web material 4 through the dye. The material passes from roll 3 over guiding devices such as the immersion rolls 5 and 6 through the liquid and onto the roll 2. When the reel of material on roll 3 has decreased to a minimum diameter, the traveling direction of the material is reversed, and the repetitive cycle is continued until the dyeing process is terminated. It is desired that the linear speed of the web material as it passes through the dye be approximately constant in order to obtain a uniform dyeing effect. The tension of the material should stay within limits that are safe for the material.

The reel core 2 is connected with the armature 7 of a motor M1 whose field winding is denoted by 8. Similarly, the reel core 3 is in connection with the armature 9 of a second reel motor M2 with a field winding 10. The connection between each motor armature and the reel core is schematically illustrated by a broken line. It normally consists of a speed-change gear or other mechanical transmission.

The two armatures 7 and 8 are series connected with current supply means represented by a generator G with an armature 11 and a separately excited field winding 12. Field winding 12 receives excitation from direct current buses 14 and 15 of substantially constant voltage. A control rheostat 16 may be series connected with field winding 12. The buses 14 and 15 may be energized from an available direct current line or by means of an exciter which may be driven at constant speed together with the armature 11 of the generator G or together with the armature of the regulating generator R mentioned below.

The field windings 8 and 10 of the two reel motors are connected in a bridge circuit which includes two resistors 17 and 18 and has two pairs of diagonal points 19, 20 and 21, 22. The diagonal points 19 and 20 are connected to the constant voltage buses 14 and 15. It will be recognized that the two field windings 8 and 10 lie in different branches of the bridge loop circuit so that they are connected in parallel with each other relative to the constant voltage supply buses.

Connected between the other diagonal points 21 and 22 of the bridge circuit is the output circuit of a source of variable regulating voltage. This source consists of a regulator, preferably an amplifying generator. Various types of amplifying generators are available for such regu-

lating purposes. The one exemplified by the drawing has its armature 23 connected with a self-exciting field winding 24 whose excitation is tuned by means of a resistor 28 so as to approximately coincide with the ascending unsaturated and substantially linear portion of the no-load saturation characteristic of the generator so that it supplies most of the excitation needed to maintain the output voltage of the generator at any value along the just mentioned linear portion of its characteristic. We prefer adjusting the self-exciting field of the regulating generator R to an "undertuned" condition so that the self-excitation of this machine is somewhat below that required to sustain its output voltage. This prevents speed build up during the winding operation and reduces speed variations, thus improving the stability of the winding performance.

Regulating generators of the type applicable for the invention require additional control field windings in order to shift the output voltage to higher or lower values along the characteristic. In the drawing, the additional windings of generator R are denoted by 25, 26 and 27. Winding 25 provides a normally constant pattern field of adjustable magnitude and is connected across the constant voltage buses 14 and 15 through a reversing switch 30 and in series with an adjusting rheostat 30. The field winding 26 is connected across the motor armature 9 to be excited in accordance with the voltage across the armature 9. Field winding 27 is similarly connected across the motor armature 7. The field windings 26 and 27 provide cumulative pilot excitation for the regulating generator R in opposition to the field of pattern field winding 25.

It was mentioned that the motor field windings 8 and 10 are connected in parallel to each other across the constant voltage buses 14 and 15. Relative to the armature circuit of the regulating generator R, however, the two field windings 8 and 10 are connected in series relation to each other. Consequently, the variable regulating voltage supplied by the regulator is additive in one motor field winding but subtractive in the other motor field winding relative to the constant component excitation of these windings supplied from the constant voltage buses. Consequently, a change in regulating voltage has the effect of strengthening one motor field while weakening the field of the other motor. For optimum results the two motor field windings should be rated to operate mainly within the unsaturated region of their characteristics throughout the desired range of control.

The two pilot field windings 26 and 27 provide a control field for the regulator R whose strength is proportional to the absolute sum of the two voltages of motors M1 and M2.

A system as described above permits the desired rewinding operation while maintaining the linear driving speed approximately at a value determined by the selected setting of the pattern field rheostat 30 and also maintains the tension in the winding material with satisfactory narrow limits. However, for obtaining accurate results, especially as regards the tension control, the current supply means for energizing the motor armatures should furnish a substantially constant current. For that reason, we prefer using a generator G of substantially constant output current, such generators being known and available under the name "shovel type generator".

With the armature currents of motors M1 and M2 being constant, the armature voltages ap-

plied to the pattern field windings 26 and 27 are proportional to the power being handled at the terminals of the two motors. Therefore, the sum of the speed-timing torque values of both motors is substantially constant.

The performance of the system will be readily understood if one considers first an operating moment at which the two reels of material have about equal diameters. As mentioned, the two motors are so connected that each exerts torque in the direction to wind up the material on its own reel. This introduces tension into the material. If we now assume that, at the just considered moment, one of the motors is exerting more torque than the other because of the difference in the strength of the respective motor fields, then the stronger motor operates as a drive and overhauls the other motor which then operates as a generator. If no limit were placed on the voltage which could be obtained from the power supplying generator G, then the drive would keep on accelerating. However, since the fields of the two motors are controlled by the regulator R in such a manner as to hold constant the sum of the two motor armature voltages, the speed of the material is established at an approximately constant value from empty to full reel. As the growing reels builds up, the drive will tend to slow down due to the increase in torque requirements at the take-up reel. The sum of the armature voltages of the two motors will then tend to decrease. As a result, the pilot field of the regulator R incites a control action which changes the output voltage of the regulator and hence varies the respective excitation of field windings 8 and 10 in the sense required to increase the sum of the armature voltages. Thus the wind-up motor field becomes stronger and this motor exerts more torque. This regulating action continues from empty to full wind-up reel diameter.

It will be recognized that the control system performs the speed and tension controlling functions despite the fact that no direct measurements of speed and tension are required. As a result, the desired operation is achieved by means of simple and reliable system components which require but a minimum of supervision and maintenance.

It is assumed in the foregoing description of the illustrated example that the reel drive is reversed by means of the switch 30 which reverses the polarity of the pattern field excitation of the regulator R. This reversal, of course, is normally effected automatically by means of limit switches (not illustrated).

While in the illustrated example we have shown resistors 17 and 18 as part of the motor field circuit, it is obvious that resistor 17 may be replaced by another field winding on motor M2 to act cumulatively with field winding 18, and that resistor 18 may be replaced by a similar additional field winding on motor M1. The network which includes the motor field windings 8 and 10 can be modified in various other ways as long as the design is such that the two field windings are parallel connected to one of the two alternating voltage sources but series connected with the other voltage source so that a variation in the voltage of the regulating source strengthens one motor field and weakens the other.

It will be understood by those skilled in the art that systems according to the invention can be modified and altered as regards details other than those specifically mentioned in this disclosure and consequently may be incorporated in

diagrams other than the one shown on the drawing, without departing from the essence of the invention and within the essential features defined by the claims annexed hereto.

We claim as our invention:

1. A control system for a rewinder drive, comprising two winder motors each having an armature and a field winding, current supply means, said two armatures being connected in series with each other to said current supply means with such polarities of connection as to produce respective torques in the wind-up sense, constant voltage supply means, said two field windings being connected in parallel to each other to said voltage supply means, a regulator having an output circuit for providing variable regulating voltage and having two control circuits for jointly controlling said regulating voltage, said two field windings being also connected with said output circuit so that said regulating voltage strengthens the resultant excitation of one and weakens that of the other winding, and said control circuits being connected across said respective armatures for controlling said regulator to maintain the sum of the voltages across said armatures substantially constant.

2. A control system for a rewinder drive, comprising two winder motors each having an armature and a field winding, current supply means, said two armatures being connected in series with each other to said current supply means with such polarities of connection as to produce respective torques in the wind-up sense, a bridge circuit having four loop-connected branches and two pairs of diagonal points, voltage supply means of substantially constant voltage connected across one pair of said points, a regulator having an output circuit connected across said other pair of points to provide variable regulating voltage, said field windings being disposed in different branches of said bridge circuit so that said constant voltage and said regulating voltage are additive in one winding and subtractive in the other, said regulator having two cumulative control circuits for jointly controlling said regulating voltage, and said control circuits being connected across said respective armatures.

3. A control system for a rewinder drive, comprising two winder motors each having an armature and a field winding, current supply means, said two armatures being connected in series with each other to said current supply means with such polarities of connection as to produce respective torques in the wind-up sense, a bridge circuit having four loop-connected branches and two pairs of diagonal points between said branches, constant voltage supply means connected across one pair of said bridge points, said field windings being disposed in adjacent branches respectively of said bridge in parallel connection with each other relative to said voltage supply means, and a regulator having an output circuit connected across said other pair of bridge points to impress variable regulating voltage thereon and having two cumulative control windings for controlling said regulating voltage, said control windings being connected across said respective armatures for controlling said regulator to maintain the sum of the voltages across said armatures substantially constant.

4. A control system for a rewinder drive, comprising two winder motors each having an armature and a field winding, current supply means, said two armatures being connected in series with each other to said current supply means with

such polarities of connection as to produce respective torques in the wind-up sense, constant voltage supply means, said two field windings being connected in parallel to each other to said voltage supply means, a regulating generator having an armature circuit to provide variable regulating voltage and having a pattern field circuit and two mutually cumulative pilot field circuits differentially related to said pattern field circuit, said motor field windings being connected with said armature circuit in inverse relation so that said regulating voltage strengthens the resultant excitation of one and weakens that of the other motor field winding, and said two pilot field windings being connected across said respective motor armatures for causing said generator to maintain the sum of the voltages across said motor armatures at a substantially constant value determined by the excitation of said pattern field circuit.

5. A control system for a rewinder drive, comprising two winder motors each having an armature and a field winding, current supply means, said two armatures being connected in series with each other to said current supply means with such polarities of connection as to produce respective torques in the wind-up sense, a bridge circuit having four loop-connected branches and two pairs of diagonal points, voltage supply means of substantially constant voltage connected across one pair of said points, a regulating generator having an armature circuit connected across said other pair of points to provide regulating voltage for strengthening the excitation of one field winding and weakening the excitation of the other field winding, said regulating generator having a pattern field winding connected to said voltage supply means to receive normally constant excitation and having pilot field means differentially related to said pattern field winding, said pilot field means having two cumulative circuits connected across said respective motor armatures.

6. A control system for a rewinder drive, comprising two winder motors each having an armature and a field winding, current supply means, said two armatures being connected in series with each other to said current supply means with such polarities of connection as to produce respective torques in the wind-up sense, a bridge circuit having four loop-connected branches and two pairs of diagonal points between said branches, constant voltage supply means connected across one pair of said bridge points, said field windings being disposed in adjacent branches respectively of said bridge in parallel connection with each other relative to said voltage supply means, and a regulating generator having an armature circuit connected across said other pair of points to provide regulating voltage and having a pattern field winding and two pilot field windings for jointly controlling said regulating voltage, reversing switch means connecting said pattern field winding with said voltage supply means, said pilot field windings being both differentially related to said pattern field winding and connected across said respective motor armatures.

7. A control system for a rewinder reel drive, comprising two reel motors each having an armature and a field winding, current supply means, said two armatures being connected to said current supply means, two voltage supply means of which one has substantially constant voltage while the other has an amplifying regulator for

providing variable regulating voltage, said field windings being connected in parallel relation to each other with one of said voltage supply means and being connected in series relation to each other with said other voltage supply means, said regulator having two cumulative control circuits connected across said respective motor armatures.

8. A control system for a rewinder reel drive, comprising two reel motors each having an armature and a field winding, current supply means, said two armatures being connected to said current supply means, two voltage supply means of which one has substantially constant voltage

while the other has an amplifying generator having an armature circuit for providing variable regulating voltage, said field windings being connected in parallel relation to each other with one of said voltage supply means and being connected in series relation to each other in said armature circuit, said generator having field control means comprising two cumulative field excitation circuits connected across said respective motor armatures.
